RECORD REPEATER

Lloyd J. Andres, Chicago, Ill., assignor to Automatic Instrument Company, Grand Rapids, Mich., a corporation of Michigan

Application July 6, 1936, Serial No. 89,049

11 Claims. (Cl. 274—15)

This invention relates in general to a phonograph mechanism for automatically repeating the playing of a record without the attention of an operator and has more particular reference to the controlling devices by which such repeating is effected.

Among the objects of the invention are; to provide for the proper playing of disc records of various diameters by manual lateral adjustment of the pickup arm carriage and the longitudinal adjustment of the pickup arm; to provide a fully adjustable pickup arm cut-off device which is both positive and sensitive; to provide a constant pickup arm pressure maintained by an adjustable counterweight; to provide a separate motor and associated mechanically operated switches to operate the pickup arm only; to provide a single unidirectional cam to control the necessary movements of the pickup arm; to provide a fully automatic repeating mechanism with a minimum number of parts exclusive of the turntable and the driving motors; to provide a record repeater which is adapted to be used in connection with a multiple switch mechanism for controlling electrical devices in a predetermined time relation with sound produced by a phonograph record; to provide a record repeater for transmitting a number of electrical impulses at each rotation of the disc record for controlling the operation of electroresponsive devices in timed relation to the record; and in general to produce the mechanism herein shown and described.

In the accompanying drawings illustrating a preferred embodiment of the invention,

Fig. 1 is a plan view of a disc record repeater with the record supporting table and pickup arm omitted;

Fig. 2 is a side elevation with parts in section of the mechanism shown in Fig. 1 and with the disc supporting table and the pickup arm in place;

Fig. 3 is a detail elevation showing the cut-off switch mechanism and the uni-directional cam for the pickup arm;

Fig. 4 is a sectional view of the cut-off switch;

Fig. 5 is a sectional view taken on the line 5—5 of Fig. 4;

Fig. 6 is a development of the pickup arm cam;

Fig. 7 is a view showing the cam which raises and lowers the pickup arm;

Fig. 8 is a top view showing the weight adjusting means of the pickup arm; and

Fig. 9 is a wiring diagram for the machine.

In operating a phonograph and using it to

control various visual and sound devices for various displays and demonstrations, it is desirable to repeat the operation of the phonograph indefinitely without giving manual attention thereto. This invention therefore relates particularly to a phonograph of this type in which the mechanism is capable of rapid and accurate adjustment to accommodate it easily and with as little change as possible to records of different sizes, operated at different speeds, to different record grooves, and to recorded records of different lengths. Provision is also made for repeating either manually or automatically.

Referring now more particularly to the drawings, a repeater phonograph mechanism is shown in Figs. 1 and 2 comprising a base 10 having a motor housing 11 suitably secured thereto for receiving a motor and suitable reduction gearing for driving a shaft 12 pointed on the upper end to receive the central perforations of disc records and for rotating a turntable 13 for supporting the records. A speed controlling lever 14 is mounted at the top of the motor housing and has a free extremity movable toward the designations S and F designating fast and slow to increase or decrease the driving speed of the motor.

At the top of the housing and below the turntable is an angular cam 15 rotatable with the driving shaft and the angular extremities are engageable with a spring contact member 16 for making an electrical contact at each engagement with a relatively fixed contact member 17, the contact members 16 and 17 being held in position by an engaging clip 18.

In the base at one side of the motor housing is a substantially rectangular opening 20 disposed at an angle to the sides of the base itself and forming a recess for a carriage 21 movable lengthwise of the motor and mounted to slide upon bars 22 and 23 carried at the ends by frame projections 24. The rods extend through projections or lugs 25 at the upper side of the carriage, and one of the rods 22 has a threaded portion at one end extending through a corresponding threaded portion in the adjacent lug 25 so that by rotating this rod by means of a squared end 26 or a slot 27 at the end of the rod the carriage can be accurately adjusted and set with respect to the turntable shaft for varying the position of the tone arm as hereafter set forth.

Mounted in a hollow post 30 extending uprightly from the carriage is a rotatable shaft 31 having a cross head 32 at the top having a 55

shoulder portion for engaging the pivoting ears 33 of a cam plate 34 by means of adjustable pivots 35. This cam plate extends below the head 32 and an adjusting screw 36 is inserted through an opening 37 in a projection 38 of the head for limiting the upward and downward pivotal movement of the cam plate. Also pivoted in opposite projections 39 of the cross head is a pickup arm 40 having a bell base 41 with opposite pivots 42 extending into the cross head projections 39 so that the pickup arm is substantially balanced but rests upon the cam plate 34 so that it is rocked thereby but the pickup arm is also free to rotate in a direction away from the plate for inserting a new stylus if desired.

The pickup arm has a pickup head 43 at one end with a stylus 44 projecting therefrom and held adjustably in place by a fastening screw 45. For playing records of different sizes the carriage 21 is adjustable in position toward and from the record shaft 12 and the pickup head is correspondingly moved for accurately setting the stylus to engage in the grooves of and to move over the record in the proper direction.

In order to maintain a constant stylus pressure on the record, a counterweight 46 is provided for the opposite end of the pickup arm which is preferably made hollow to receive the head 43 and the counterweight, with slots 47 and 48 through which extend fastening screws 49 and 50 connected by links 51 and 52 respectively to opposite ends of a central pivoted ratio plate 53. It will be noted that one link may be connected at a different distance from the center of the plate than the other so that the movement of the plate properly positions both the head 43 and the counterweight 46 and when the proper adjusted position is obtained one or both of the fastening screws is tightly inserted thereby engaging the edges of its slot and locking the parts in the adjusted position. To raise and lower the cam plate 34 and also the pickup arm 40 a circular cam 55 is secured to a horizontal shaft 56 below the plate mounted in carriage supporting posts 25 extending upwardly. This cam has a flat portion 57 at one side which allows the cam plate to fall below a position where the pickup arm bell 41 rests upon it so that during the playing of a record the pickup arm is supported by the stylus in engagement with the record and under the constant pressure determined by the counterweight adjustment.

Attached laterally to the cam 55 and preferably formed as an integral part thereof is a cam 58 having a varying rim 59 spaced from the cam 55 and adapted to engage a pin or projection 61 extending downwardly from the plate 34. This cam has a wide portion 62, a gradually narrowing portion 63, a straight narrow portion 64, an outwardly extending narrow portion 65, and a straight narrow portion 66, which terminates in the side portion 62 so that as the cams 55 and 59 are rotated the cam plate is raised and lowered and swung laterally in accordance with the movement of the cams.

In order to rotate the cams 55 and 59, a driving gear 70 is attached to the shaft 56 which is connected by a reduction gearing 71 to the drive shaft of a small electric motor 72 mounted on the carriage 21, preferably secured to the rear post 25 and movable with the carriage. The arrangement of the parts is such that the motor 72 rotates the shaft 56 and the attached cams one complete rotation for each playing of a record

and the motor is actuated automatically at the completion of any record to raise the pickup arm to rotate it to starting position and to lower it into engagement with the record if it is to be repeated.

As a record is played the engagement of the stylus with the grooves of the record carry the pickup arm toward the center of the record and as the cam plate 34 is then located opposite the flat portion 57 of its cam 55, the playing movement of the tone arm moves the cam plate 34 about the axis of the shaft 31 until the playing of the record is complete. At this time a cut-off switch is engaged by an adjustable contact member carried by the cam plate 34 which closes an electric circuit to the motor 72. This mechanism comprises a threaded block 73 at the underside of the cam plate 34 adjustably held in place by a thumb screw 74 at the top of the plate and with a long contact screw 75 extending through the block and adjustable therein by a knurled head 76. Beyond the driving gear 70 is a mercury switch for controlling the pickup arm motor 72 comprising a housing 78 supported by a bracket 79 from the adjacent carriage post 25. Projecting from the top of the housing is a lever 80 having a bent extremity 81 in the path of the end of the cut-off contact screw 75 and the lower end of this lever has a pivot 82 upon which it is mounted on the lower arm of a lever 83 having its pivot 84 at the top of the housing 78 and having slotted arms 85 between which the upper end of the lever 86 is movable. The lower end of the lever 80 beyond its pivot has a projection 86 engaged by one end of a spring 87, the other end of which is secured to a fixed portion of the housing 78 so that the spring tends to hold the upper end 81 of the lever in the path of the screw 75. Mounted on a shaft 80 extending through the housing 78 is a cam 81 having a notch 82 adapted to be engaged by a pointed extremity 83 of the lever 80, and the cam is limited in its movement by a set screw 84 extending through the wall of a housing 78 into position to engage a flat portion 95 on the cam 81. Outside of the casing this shaft carries a spring engaging clip 86 for holding a glass mercury holding bulb 97 for making contact between conductors 98 and 99. It will be understood that when the bulb 97 is in one position the mercury makes connection between the terminals of the conductors and when in a different inclined position the electrical connection between the contacts is broken.

In order to prevent the open circuiting of the mercury switch, the mounting lever 83 has a projection 100 extending through an opening in its housing 78 to engage a raised portion or projection 101 on the shaft driving gear 70 and attached to the ends of the arms 85 is one end of a spring 102, the other end of which is attached to a fixed portion of the housing 78 so that it tends to press the projection 100 in the direction of the gear 70. When this gear is in a position where the projections 100 and 101 do not engage the lower end of the lever 83 it moves the lower end of the lever 80 so that it is out of the path of movement of its cam 81 and even though the lever 80 is actuated during this time it will not affect the operation of the mercury switch. The switch is normally held in switch closing position by a spring 89 inserted at one end on the shaft 80 extending loosely around it and having its other end hooked over the bracket 79 so that it tends always to tilt the bulb 97 to switch closing position. When the gear 70 is moved so that its pro-

jection engages the projection 100, the lever 83 is rocked against its spring 102, the lower end of the lever 83 is moved toward the cam 91 and the engaging pointed extremity 93 of the lever 80 engages the notch 92 of the pawl rocking the switch bulb 97 against its spring 89 to circuit opening position. When the upper extremity 81 of this lever is engaged by the record cut-off device including the adjustable screw 75, the pointed end 93 of the lever 80 is rocked out of engagement with the notch of the cam 91 thereby allowing its spring 89 to close the switch.

At one end of the cam shaft 56 is a cam 103 having a flat portion 104 for engaging a spring contact arm 105 for making connection with a spring contact arm 106.

Supported by one of the carriage posts 25 adjacent the end of the shaft 56 is a bracket 107 in which spring contacts 108 and 109 are mounted in spaced apart relation which are separated by a projection 110 carried by the cam plate 34 when it is returned to the starting position. This separates the contacts and prevents the automatic replaying of a record when the pickup arm is returned to the starting position. A record repeating connection comprises a central spring contact 111 and two relatively fixed contacts 112 and 113 on opposite sides thereof. The central contact has a projection 114 engaged by a flat portion 115 of a cam 116 near the end of the shaft 56 so that when the projection is in engagement with the flat portion it makes electrical connection between the central contact 111 and one of the side contacts 112 but when it is engaged by the remainder of the cam it makes continuous connection with the other contact 113.

Although the switch contacts 108 and 109 and 111, 112 and 113 and their associated cams and connections as well as the contacts 16 and 17 and 40 its cam 15 operated by the record motor are shown in connection with this phonograph, they are connected in series for electric robophone operation as shown in connection with the application of Andres and Magruder for Electric robophonograph, filed May 18, 1936, Serial No. 80,360, and the present repeater mechanism forming the subject matter of this application may be shown in a relatively simple wiring diagram as shown in Fig. 9.

At one side of the base is a manual switch 117 having conductors 118 and 119 for connecting it to one of the conductors 99 of the mercury switch and thence to one of the switch contacts 106 and the other conductor 119 being connected to the other switch contact 105 which is actuated by the cam 103. The other terminal 98 of the mercury switch is connected by a conductor 120 to one side of the carriage motor 72; and the conductor 119 is connected by a conductor 121 with one of the electrical supply means 122 while the other side of the motor is connected by a conductor 123 to the other electrical supply main 124. These electrical supply mains 122 and 124 extend directly to the turntable motor and a main switch 125 controls the supply of current to the turntable motor and through the switches as now described to the carriage motor.

For a single operation of the carriage motor, assuming the main switch 125 to be closed, the manual switch 117 is closed temporarily which closes a circuit from main 122 through conductors 121 and 119, switch 117, conductor 118, mercury switch and its conductors 99 and 98, conductor 120 to the motor 72, and thence through conductor 75 123 to the other main 124. To repeat the play-

ing of the record the manual switch 117 is left closed but if it is opened after starting the motor the cam 103 will maintain the contacts 105 and 106 together during an entire rotation of the cam 103 by its shaft 56 until the flat side 104 is engaged by the contact 105, thus opening the connection between the contacts 105 and 106 and opening the connection to the carriage motor 72.

During playing of a record the operation of the carriage motor is controlled by the cam 56, the mercury switch and the cut-off device; the mercury switch being closed the projection 100 being in advance of its engagement with the projection 101 on the wheel 70. Closing the manual switch 117 energizes the carriage motor 72 as above set forth, the flat portion 57 of the cam 55 moves under the cam plate 34, allowing the pickup arm to lower the stylus 44 into engagement with the grooves of the record. At this time the projection 100 of the mercury switch lever 83 rides up on the projection 101, turning the mercury switch bulb to open position, thereby shutting off current and stopping the carriage motor. This allows the pickup arm with the stylus riding in the record grooves to swing laterally about its vertical axis, the projection 61 of the cam plate 34 thereupon being movable in the wide portion 62 of its cam and the tone arm moving in this direction until the cut-off bar 75 engages the upper end of the cut-off lever 80 of the mercury switch. This causes the engaging point 93 to be rocked downwardly out of engagement with cam 91, thereby releasing the mercury switch bulb 97 and connecting the conductors 98 and 99 so that the energizing circuit is closed to the carriage motor 72 through the mercury switch. Movement of the motor actuates the shaft 56 and the cam 58 which engages the post 61 of the cam plate 34, moving it laterally toward the starting position and into the reduced passage 64 of the cam groove. At the same time the cam 55 has been rotated with the shaft 56, first raising the cam plate 34 and the pickup arm from playing position and as the tone arm is rotated to the starting position it is raised and kept in elevated position so that its stylus will not engage or mar the grooves of the record. When the shaft 56 has rotated sufficiently to bring the flat portion of cam 103 to engage the spring contact 105, the connection between contacts 105 and 106 is broken and if at the same time the repeating switch 117 is also open, the carriage motor 72 will stop and the playing of the record will not be repeated. However if the switch 117 is closed the playing of the record will be repeated in the same cycle as before.

With this construction and operation of the parts a record may be played once or repeated as many times as desired without any manual attention thereto. A phonograph repeater of this kind is particularly adapted to be used in connection with visual and sound devices which may be actuated in timed relation to the record which is being played.

I claim:

1. In a phonograph, a pickup arm and means for mounting it intermediate its ends to swing and tilt, means for movably supporting a record engaging stylus at one end, a counter-weight movable at the other end, and an adjustable connection between the said supporting means and the counter-weight for moving one in proportion to the movement of the other for playing records of different sizes and for varying the pressure of the stylus on a record.

2. In a phonograph, a turntable for a record, a pickup arm and a carriage therefor on which the pickup is pivoted, the carriage being slidable at an angle away from the turntable for adjusting the location of the pivot of the arm with respect to the turntable for playing records of different sizes, a counter-weight and a stylus movably carried by the arm, and means for proportionately adjusting the position of the stylus and the counter-weight in varying the length of the radius of movement of the stylus in playing records of different sizes.

3. In a phonograph, a pickup arm, means for mounting the arm intermediate its ends for rotational and tilting movement, the arm comprising a hollow frame with slots at the ends, a stylus support slidable within the frame at one end, a counter-weight within the frame at the other end, means extending through the slots and connected to the stylus and the counter-weight on top of the arm for proportionately adjusting the radial length of the stylus support and the counter-weight with respect to the axis of the arm for playing records of different sizes.

4. In a phonograph repeater having a turntable with a motor therefor and a pickup arm for engagement and swinging movement by records thereon, means including a unitary rotatable cam for raising, lowering and swinging the arm, a separate motor for driving the cam, and means for starting and stopping the latter motor independent of the movement of the turntable, said means including a switch, a gear operated by the motor to open the switch, and a projection carried by the pickup arm to close the switch.

5. In a repeating phonograph, a pickup arm moved by engagement with a record from a starting to a finishing position and means for mounting it to swing and tilt, a cam having a peripheral portion to raise and lower the arm and another laterally extending portion to swing the arm, and another laterally extending portion to permit a free swinging movement of the arm without engaging it, a motor for driving the cam, and electric controlling means for the motor to stop it and the cam when the cam is in the position allowing the arm to swing freely from starting to finishing position thereof said means including a switch, and a gear operated by the motor having a projection to engage and open the switch at predetermined times.

6. In a phonograph for repeating the same record, a pickup arm mounted to swing in playing a record, rotary cam means for moving the arm from finishing to starting position and having a portion allowing the arm to swing freely from starting to finishing position, a motor for the pickup arm and its cam, an electric switch for controlling the motor, a cam driven by the motor to open the switch while the arm is moving from starting to finishing position, the switch being closed by a projection carried by the arm for starting the motor as soon as the arm reaches its finishing position and the first said cam then returning the arm to its starting position.

7. In a reciprocating phonograph, a pickup arm movable to swing in engagement with the grooves of a record from starting to finishing position, a cam having a portion allowing the arm to swing freely in playing position, and a portion to engage the arm for swinging it from finishing to starting position, a motor for driving the cam in one direction, a switch for controlling the motor, a cam operated by the motor to operate the

switch and open the motor circuit when the arm is in record playing position, a cut-off device carried by the arm and lever means engaged thereby for closing the switch and reclosing the circuit to operate the motor, rotating the first cam to raise the arm from a record, and a limit switch including a gear operated by the motor for opening the switch and the motor circuit after the playing of a record moves the arm to the finishing position.

8. In a phonograph, a continuously rotatable turntable motor, a movable pickup arm moved by engagement with a record from a starting to a finishing position, a separate motor and means operated thereby for raising, lowering and moving the arm from finishing to starting position, a tilt switch in circuit with the arm motor having a cam wheel driven by this motor to open the switch when the arm is lowered into playing position, a trip lever for closing the switch and an adjustable projection carried by the arm for engaging the lever in finishing position, and spring means in connection with the switch for holding it in circuit closing position except when engaged by the cam of said wheel in record playing position.

9. In a phonograph, a turntable motor, a movable pickup arm pivoted to tilt and to swing and moved by engagement with a record from a starting to a finishing position, cam means for raising, lowering and moving the arm upon its pivots from finishing to starting position, a separate cam motor, a circuit breaker for the cam motor, trip mechanism operated by the arm in finishing position for actuating the breaker to close the circuit, a stop switch operated by the arm moving cam and in series with the circuit-breaker, and a repeater switch connected in parallel with the stop switch circuit and operative when closed to nullify the stop operation of the stop switch.

10. In a phonograph, a turntable and a motor for operating it continuously, a movable pickup arm pivoted to tilt and to swing and moved by engagement with a record from a starting to a finishing position and a separate motor for raising, lowering and moving the arm from finishing to starting position upon its pivots, switch means in circuit with the arm motor for stopping it when the arm is in playing position, means for closing the switch when the arm is in finishing position, and a double circuit in series with the switch having a stop switch and a cam therefor operated by the arm motor and a manual switch for starting and repeating the operation of the arm motor independent of the said stop switch or the turntable motor.

11. In a phonograph, a movable pickup arm pivoted to tilt and to swing and moved by engagement with a record from a starting to a finishing position, a separate motor for pivotally raising, lowering and moving the arm from finishing to starting position, two switches in a series circuit for controlling the operation of the motor, one switch being operated by a cam carried by the motor to open the circuit each time a record is played and the arm returned to starting position, the other switch having a cam operated by the motor for opening it when the arm is lowered to playing position and a trip lever engaged by the arm for closing it when the arm is in finishing position, and a manual repeater switch which when operated momentarily closes a circuit to start the motor for one-playing of a record and is left closed for repeating the playing of a record.

LLOYD J. ANDRES. 75
